UNITED STATES PATENT OFFICE.

ROBERT S. RILEY, OF PROVIDENCE, RHODE ISLAND, ASSIGNOR TO THE AMERICAN SHIP WINDLASS COMPANY, OF PROVIDENCE, RHODE ISLAND, A CORPORATION OF RHODE ISLAND.

STOP MECHANISM FOR WINCHES.

1,117,910.

Specification of Letters Patent.

Patented Nov. 17, 1914.

Application filed January 20, 1911. Serial No. 603,666.

To all whom it may concern:

Be it known that I, ROBERT S. RILEY, a citizen of the United States, and a resident of Providence, Providence county, Rhode Island, have invented certain Improvements in Stop Mechanism for Winches, of which the following is a specification.

One object of my invention is to provide a relatively simple form of mechanism whereby a gipsy or winch head may be driven from a line shaft, preferably extending at right angles to the axis of revolution of said head; the invention also contemplating novel means whereby the winch head may be instantaneously disconnected from the driving shaft and thereafter immediately locked from turning in a reverse direction.

A further object of the invention is to provide a gipsy or winch head with novel means whereby it is normally maintained in operative connection with a continuously driven shaft or other source of power while being capable of being disconnected therefrom and locked in such position that it can not turn in a direction opposite that at which it has been driven; the invention also contemplating an improved clutching device for permitting the driving or holding 30 of the gipsy head, as well as means whereby the clutching device may be locked in one of its several positions.

These objects and other advantageous ends I secure as hereinafter set forth, reference being had to the accompanying drawings, in which:—

Figure 1, is an elevation, partly in vertical section, illustrating the detail features of my invention; Fig. 2, is a plan of the apparatus shown in Fig. 1; Fig. 3, is a vertical section on an enlarged scale showing the construction of the foot operated plunger, and Fig. 4, is a side elevation of the clutching device.

In the above drawings, 1 represents any suitable supporting structure such as the deck of a vessel, a wharf, or the like, shown as mounted upon a metal structure 2 carried on channels 3. On this support is mounted 50 a casting 4 constituting a bearing for a vertical shaft 5, to the upper end of which is fixed the gipsy or winch head 6. The lower end of said shaft has fixed to it a beveled gear 7 which meshes with a beveled pinion 8 fixed to and in the present instance form-

ing part of a sleeve 9 loosely mounted on a continuously driven line shaft 10. One of the bearings for this shaft is indicated at 11; the sleeve 9 being journaled in this bearing and itself serving to directly support the 60 shaft. Fixed to said shaft is a clutch sleeve 12 having a series of teeth 17 on that one of its edges which is directed toward the loose sleeve 9. A third sleeve 13 is slidably mounted on a bushing carried by the shaft 65 10 and also upon the sleeve 9 so that it is free to move longitudinally of this latter, to which it is fixed, however, by splines 9a. That face or edge of the bearing 11 adjacent this movable sleeve 13 is provided with a 70 set of teeth 14 and said sleeve has one set of teeth 15 adjacent the teeth 14 and a second set of teeth 16 adjacent the set of teeth 17 on the sleeve 12. Within the slid- 75 able sleeve 13 and abutting on one end of the sleeve 9 is a spring 18 acting on said movable sleeve so as to normally maintain its teeth 16 in engagement with the teeth 17 of the sleeve 12.

For the purpose of sliding the sleeve 13, 80 I pivot a bell crank lever 19 to the bearing structure 11 and make one of its arms in forked or branched form so as to extend around said sleeve 13, providing said arm with pins 20 designed to enter an annular 85 recess 21 of the sleeve. The other arm of the lever is connected to the trunnions 22 of a block 23, mounted, as shown in Fig. 3, on a stud 24 screwed into a plunger 25, which is guided in the deck or other structure 1 90 by means of a casting 26 in the form of a bushing. The plunger 25 is provided with a shoulder 27 preferably at or adjacent its upper end, and there is slidably mounted in the casting 26 so as to be movable toward 95 and from said plunger, a bolt 28 whose head is formed to engage the shoulder 27 when the plunger is in its lower position in order to retain it in such position.

Under operating conditions, the line shaft 100 10 is continuously driven from a suitable source of power, and inasmuch as the spring 18 holds the slidale member 13 in such position that its teeth 16 engage the teeth 17, power is transmitted from said 105 shaft through the sleeves 12, 13 and 9 to the beveled pinion 8, through the gear 7, to the shaft 5 and to the winch or gipsy head 6. This head is used in the well known way for hoisting or any other 110

purpose and if at any time the cable employed upon it should foul or it should become necessary for any other reason to disconnect said head from the source of power, 5 the plunger 25 is pushed down by the foot of the operator, thereby turning the bell crank lever 19 on its pivot. The sleeve 13 is thus disengaged from the teeth 17 of the sleeve 12 and immediately thereafter the 10 teeth 15 of said sleeve 13 are engaged with the fixed teeth 14 on the bearing structure 11, so that not only is the gipsy head no longer driven, but by reason of the construction and placing of the two sets of teeth, it 15 is immediately thereafter locked or held from turning in a direction the reverse of that at which it has previously been turned.

If the pressure be removed from the plunger 25, the spring 18 immediately returns 20 the sleeve 13 into its normal position with its teeth 16 in engagement with the teeth 17, thereby again causing the gipsy head to be driven from the shaft 10. On the other hand if it be desired that the head be retained in its locked position in order to hold a load, the bolt 28 is moved longitudinally 25 while the plunger 25 is depressed, thereby bringing its head into engagement with the shoulder 27 and preventing upward movement of the plunger and disengagement of the teeth 15 from the teeth 14 under the action of the spring 18.

If when the gipsy head is disconnected from the shaft 10 it should tend to continue 35 to spin or turn, the pressure exerted upon the plunger 25 causes the teeth 15 on the sleeve 13 to bear against the teeth 14 on the bearing structure, so that these latter exert a retarding influence which quickly brings the 40 head to rest.

I claim:

1. The combination of two concentric shafts; a clutch member fixed to one shaft; a fixed clutch member; a third clutch member rotatably connected to one of the shafts while free to slide thereon and loose on the other shaft; with means for moving said third clutch member into engagement with either of the other clutch members at will.

50 2. The combination of two concentric shafts; a clutch member fixed to one shaft; a power transmitting member fixed to the other shaft; a movable clutch member loosely mounted on one shaft and rotatably connected to the other; a fixed clutch member between said movable clutch member and the power transmitting member; and means for causing the movable clutch member to engage either of the other clutch 55 members at will.

60 3. The combination of two concentric shafts; a clutch member fixed to one of said shafts; a fixed clutch member; a third

clutch member movably connected to one of the shafts; means for moving said last 65 clutch member into engagement with either of the other clutch members; and a spring mounted within the third clutch member and acting between it and one of the shafts to move it toward the first clutch member. 70

4. The combination of a driven shaft; a gear connected thereto; a driving shaft; a sleeve loosely mounted thereon; a gear fixed to said sleeve and meshing with the first gear; a fixed structure having teeth; a 75 toothed member fixed to said driving shaft; and a movable member permanently connected to said sleeve and movable at will into engagement either with the teeth of the fixed structure or with the teeth of the member on the driving shaft.

5. The combination of a driven shaft; a driving shaft; a sleeve loosely mounted on said driving shaft and operatively connected to said driven shaft; a fixed structure 85 having teeth; a toothed member fixed to said driving shaft; and a movable member permanently connected to said sleeve and movable at will into engagement either with the teeth of the fixed structure or with the teeth 90 of the driving member on the driving shaft; a lever for operating said movable member; and foot operated means for actuating said lever.

6. The combination of a driven shaft; a 95 driving shaft; a sleeve loosely mounted thereon and operatively connected to said driven shaft; a sleeve splined to said loose sleeve and having two sets of teeth; a fixed toothed structure placed to be engaged by 100 one set of teeth; a structure fixed on the driving shaft and having teeth placed to be engaged by the second of said sets of teeth on the slidable member; with means for actuating said slidable member.

105 7. The combination of a driven shaft; a driving shaft; a member permanently connected to said driven shaft and loosely mounted on the driving shaft; a slidable sleeve splined to said member and having a 110 set of teeth; a toothed structure fixed to the driving shaft; means for normally retaining the slidable sleeve with its teeth in engagement with the teeth of said structure on the driving shaft; and means for actuating said slidable sleeve to move it out of engagement with the toothed structure on the driving shaft.

115 In testimony whereof, I have signed my name to this specification, in the presence of 120 two subscribing witnesses.

ROBERT S. RILEY.
